UNITED STATES PATENT OFFICE.

JUDSON L. MCKELLAR, OF BROOKLYN, NEW YORK, ASSIGNOR TO GASAU-THOMPSON COMPANY, INC., OF BROOKLYN, NEW YORK, A CORPORATION OF NEW YORK.

CONVERTIBLE CHAIR AND COUCH.

1,405,931.

Specification of Letters Patent. Patented Feb. 7, 1922.

Application filed July 1, 1921. Serial No. 481,749.

To all whom it may concern:

Be it known that I, JUDSON L. MCKELLAR, a citizen of the United States, and a resident of Brooklyn, in the county of Kings and State of New York, have invented certain new and useful Improvements in Convertible Chairs and Couches, of which the following is a specification.

The invention relates to combined chairs and couches, and resides in the novel features, structure and combinations of parts hereinafter described, and particularly pointed out in the claims.

The object of my invention is to provide an article of furniture which may be conveniently used as a chair or extended to form a full length couch. The combined chair and couch of my invention comprises a middle section, a head or back section and a foot section, the head or back section being pivoted and adapted to be turned downwardly and at the same time, due to intermediate mechanism, effect the outwardly sliding movement of said foot section from over the middle section, the article being thus converted into a couch. When the head or back section is turned upwardly, the mechanism connecting it with the foot-section operates to slide the foot section inwardly over the middle section, whereby the article is restored to chair condition. The mechanism provided by me and operable from the head section for actuating the foot section, is so constructed that I may give the back or head section several inclined positions without disturbing the foot section, both when the sections are extended to form a couch and when they are positioned as a chair, and this is one of the desirable features of my invention, since on many occasions whether the article is used as a chair or as a couch, the head or back section may be rendered more comfortable to the user when inclined to such position as may be desired. The fact that the foot section may be slid outwardly and inwardly due to the movement of the head or back section, is also a desirable feature of my invention. Aside from general features of construction and operation, I have so constructed and disposed the operating mechanism of the article as to render the same durable, convenient of operation, compact and without complication.

The invention will be fully understood

from the detailed description hereinafter presented, reference being had to the accompanying drawings, in which:

Fig. 1 is a side elevation of a combined chair and couch embodying my invention, the members of the article being shown in their extended position forming a couch;

Fig. 2 is a plan view of the same;

Fig. 3 is a longitudinal vertical section of the same taken on the dotted line 3—3 of Fig. 2;

Fig. 4 is a side elevation corresponding with Fig. 1 and illustrating two adjusted positions of the head section of the couch from that illustrated in Fig. 1, Figs. 1 and 4 indicating that the said head section may have any of three positions;

Fig. 5 is a side elevation of the complete article of furniture shown arranged as a chair;

Fig. 6 is a corresponding side elevation showing the back member as inclined toward the vertical from the position in which it is illustrated in Fig. 5;

Fig. 7 is a rear elevation of a portion of the back of the head section and illustrates the ratchet mechanism by which the adjustments of the head section are secured;

Fig. 8 is a side elevation, partly broken away, of a modified construction of combined chair and couch embodying certain features of my invention, the parts being shown as extended to form a couch;

Fig. 9 is a side elevation of the same showing the parts telescoped to create a chair, the solid lines and dotted lines for the back section indicating the positions in which said section may be adjusted, and

Fig. 10 is a horizontal section, partly broken away, taken on the dotted line 10—10 of Fig. 8.

The combined chair and couch of my invention comprises three body sections numbered, respectively, 15, 16, 17, the section 16 constituting what may be termed a back section and the section 17 being the foot section, while the section 15 is intermediate of the sections 16, 17, and may be termed a middle or seat section. The section 15 comprises angle iron side bars 18, angle iron legs 19, and transverse angle iron bars 20 connecting said legs 19. The lower portions of the legs 19 are connected together at each side of the general frame by longitudinal bars 21 which extend rearwardly beyond the rear legs 19

100

105

110

and have at their rear ends downwardly extending members 22, which reach the floor and serve the important purpose of resisting any tilting action of the whole article during 5 the movement of the head or back section 16. The side rails 18 of the middle section 15 support a spring fabric 23 of any suitable type.

The head or back section 16 comprises side 10 bars 24, which are of angle iron construction, and an outer end bar 25 which will preferably be curved outwardly to enhance its appearance and is rigidly secured at its ends to the rear ends of the side bars 24. The side 15 bars 24 are secured by rivets 26 to the rear ends of the side bars 18 of the middle section 15, said rivets 26 serving to hinge the head or back section 16 to the middle section 15. The side bars 24 of the head or back section 20 16 support a continuation of the spring fabric 23, as shown in Fig. 2.

The back section 16 has secured to it by pivots 27 a pair of supporting legs 28, which are connected together by a brace bar 29 and 25 are deflected angularly toward the rear, as shown in Fig. 1, so that said legs may stand at an incline and efficiently brace the head or back section 16.

At the opposite side edges of the upper 30 portion of the head or back section 16 are rigidly secured, to the bars 24, toothed rack plates 30, and to the legs 28 by means of rivets 31 is pivotally secured a yoke 32 composed of side bars 33, a transverse connecting bar 34, Fig. 2, and a transverse rod 35 which connects the side bars 33 at the outer free end of the yoke. The rod 35 is provided for engagement with any of the recesses in the rack plates 30, in accordance with the 35 adjustment it may be desired for the head or back section 16. The yoke 32 is adapted to swing on the rivets 31, and the free end of said yoke, represented by the rod 35, is spring pressed in a direction toward the plates 30 by means of coiled springs 36 which are connected with the side bars 33 of said yoke and with the bars 24 of the back or head section 16. When the back or head section 16 is substantially horizontal or in a 40 position shown in Figs. 1 and 3, the rod 35 is beyond the recesses of the rack plates 30, and at such times said rack plates are not performing any function and the said head or back section 16 is supported from the floor 45 on the legs 28. When it is desired to incline the back or head section 16 from the position shown in Fig. 1 to either of the positions indicated in Fig. 4, the attendant will simply pull up on the head or back section 50 16 until the said section has reached the inclination desired, and the rod 35 during this movement will, by being acted on by the springs 36, ride against the rack plates 30 and enter the first or second recess of said plates, counting from the rear end thereof,

as illustrated in Figs. 1 and 2, arresting said head or back portion 16 when the same arrives at the desired inclination and supporting said section in such inclination, the rear legs 28 then having been elevated from the floor. When the head or back section 16 is in its inclined position shown in Fig. 4, it is desired that a weight thrust against said section shall not tilt the foot portion of the article upwardly, and hence I provide the 70 rear extensions on the side rails 21 and the vertical members 22 extending downwardly therefrom to engage the floor, said members 22 being projected toward the rear and beyond the rear legs 19, serve to resist the tilt 75 upwardly of the front portion of the article by pressure applied against the head or back section 16 thereof.

An essential feature of my invention resides in the provision of means whereby I may impart inclined positions to the back or head section 16, as shown in Fig. 4, without moving the foot section 17, and also means whereby when the back or head section is pushed toward the vertical from the inclined positions 90 shown in Fig. 4, the movement of said back or head section will operate to slide the foot section 17 over upon the middle portion 15 and thereby convert the article into a chair, and these means will presently be described. 95

The foot section 17 comprises two angle iron side bars or rails 37, front legs 38 and a transverse angle iron rung 39 connecting said front legs which are preferably equipped with rollers 40. The foot section 100 17 supports a section 41 of the mattress supporting spring-fabric. The foot section 17 has no rear legs and is entirely open at its inner or rear end to slide over upon the middle section 15 when there is no cushion or mattress on said section 15. The rear ends of the side bars 37 of the foot section 17 are pivotally secured to the upper ends of levers 42 which are preferably in the shape of tubular bars and extend downwardly to and are 105 pivotally secured by rivets 43 against the side rails 21 of the middle section 15. When the lever bars 42 are in the position shown in Fig. 1 they permit the top of the foot section 17 to lie about on the same horizontal 110 plane with the top of the middle section 15, and when said bars 42 are turned toward the rear on the pivots 43, the upper ends of said bars 42 move through the arc of a circle and lift the top of the foot section 17 115 upwardly and draw it over the top of the middle section 15, this result taking place when the head or back section 16 is turned upwardly to convert the article into a chair. In Fig. 1 I illustrate an independent cushion 120 44 on the head or back section 16, and cushions 45, 46, respectively, on the foot and middle sections 17, 15, the cushions 45, 46 being connected together by a hinge 47. When it is desired to turn the lever bars 42 125 130

rearwardly for elevating the foot section 17 and drawing it over the top of the middle section 15, the cushion 46 is turned over upon the cushion 45 so as to leave the top of the 5 middle section 15 free for the passage over it of the foot section 17. The lever bars 42 are suitably connected by an angle iron brace 48 so that said bars may move uniformly whenever actuated either to draw the foot 10 section 17 over the middle section 15 or force said foot section 17 from over the middle section 15 and to its extended position shown in Fig. 1.

The means for actuating the lever bars 42 15 to slide the foot section 17 either inwardly or outwardly, comprise the lever bars 49 pivotally secured at their outer or rear ends by the rivets 31 to the legs 28 and links 50 whose rear ends are pivotally secured, by 20 rivets 51, to the forward ends of the levers 49 and whose front ends are slotted, as at 52, and connected with the lever bars 42 by means of rivets 53 which are rigid with 25 said bars 42 and extend through the slots 52 of the links 50. The levers 49 are pivotally secured, by rivets 54, intermediate their ends to rearwardly projecting plates 55 secured to the rear legs 19 of the middle section 15. There is a lever 49 at each side of the head 30 or back section 16 and a link 50 at each side of the middle section 15, and the outer or rear ends of the levers 49 become connected together so as to have corresponding movement by reason of the rivets 51 securing them 35 to the legs 28 and yoke 32. The links 50 at the opposite sides of the middle section 15 have corresponding movement due to their engagement with the rivets 53 connected with the lever bars 42 which by being connected by the transverse bar 48 constitute 40 a rigid frame whose only movement is at the fulcrum points or rivets 43.

If it should be desired to incline the back or head section 15 upwardly, the attendant 45 will lift upwardly on the end of said head or back section, preferably pressing against the lower surface of the bar, 50 and this will result in said back section lifting the rear legs 28 from the floor and 55 in the rod 35 of the yoke 32 riding into say the first rear recess of the rack plates 30, as shown in Fig. 4. During this movement of the back or head section 16 to the inclined position shown by solid lines in Fig. 4, the rear ends of the levers 49 become 60 elevated and the forward ends of said levers are turned downwardly from the position in which they are shown in Fig. 1, traveling through the arc of a circle and turning the rear ends of the links 50 downwardly, causing 65 said links finally to have a limited rearward motion, carrying the slots 52 along the rivets 53. The imparting to the back or head section 16 of the adjustment just described to the inclined position shown by

solid lines in Fig. 4, has no influence on the lever bars 42 and consequently none on the foot section 17, and to obtain this adjustment of the back or head section 16 without disturbing the foot section 17 is one of the 70 benefits of my invention, this construction enabling me to preserve the couch effect of the article and at the same time incline the back section thereof to meet the comfort of the user. I may also without disturbing 75 the foot section 17 lift the head or back section 16 to the position shown by dotted lines in Fig. 4, the rod 35 due to the further elevation of the head or back section 16 riding into the second rear pair of recesses 80 of the rack plates 30, as I illustrate by dotted lines in Fig. 4. This further upward turning of the head or back section 16 results in the forward ends of the levers 49 being turned downwardly to a further extent or 85 to the position shown by dotted lines in Fig. 4, and in said links 50 being drawn rearwardly until the forward ends of the slots 52 therein reach the rivets 53. So long as the links 50 by the presence of the slots 52 90 are enabled to ride along the rivets 53 without moving the lever bars 42, the foot section 17 remains stationary, but after the forward ends of the slots 52 reach the rivets 53, then the further upward turning movement of the head or back section 16 will 95 result in the levers 49 pulling against the links 50 and in said links drawing against the rivets 53 and turning the bars 42 upwardly to slide the foot section 17 over upon 100 the middle section 15. If it may be assumed that the structure is in the position shown in Fig. 4, and it is desired to convert the same into a chair, the cushion 46 will be turned over upon the cushion 45, and thereupon the head or back section 16 will be turned upwardly toward the positions shown in Figs. 5 and 6, and this will result in the upper ends of the lever bars 42 turning 110 rearwardly and elevating the rear end of the foot section 16 upwardly and sliding said foot section over upon the middle section 15, or to the position shown in Fig. 5, in which it may be seen that the rear ends of the slots 52 are at the rivets 53 of the 115 lever bars 42. The back or head section 16 is shown in an inclined position in Fig. 5, and it may be desirable to move said head or back section 16 further toward a vertical plane without disturbing the foot section 17, 120 and to accomplish this purpose is one of the objects of my invention; and as shown in Fig. 6 the head or back section 15 may be turned further toward a vertical plane from the position shown in Fig. 5 by merely 125 pushing it upwardly, the pawl rod 35 then riding down into the lower recess of the rack plates 30 and the levers 49 pulling the links 50 rearwardly without affecting the lever bars 42, said links then, by reason of 130

their slots 52, riding along the rivets 53 without exerting any pressure or strain against said rivets or the bars 42. I may thus convert the article into a couch, as shown in Figs. 1, 2 and 3, and while preserving a couch effect adjust the head or back section thereof, as shown in Fig. 4, or I may convert the article into a chair, as shown in Fig. 5, and also effect the adjustments of the back or head section 16 without disturbing the foot section 17 or modifying the seat portion of the chair. When the back or head section 16 is turned upwardly to create a chair, said section may be moved directly, if desired, to the position shown in Fig. 6, and then whenever desired inclined backwardly to the position shown in Fig. 5, or the back or head section 16 may first return to the position shown in Fig. 5 and then, whenever desired, to the position shown in Fig. 6.

The levers 49 are rocking levers, and when the head or back section 16 of the article is in or about in the chair position, indicated in Figs. 5 and 6, and said section is pressed downwardly toward a horizontal position, the levers 49 turn on the pivots 54 and the lower ends of said levers 49 force the links 50 forwardly to effect through the lever bars 42 the forward sliding movement of the foot section 17, and at the same time the upper ends of said levers 49 force the rear legs 28 outwardly so that when the head or back section 16 reaches its nearly horizontal position, said legs may engage the floor and serve as supports for said section 16. When the head or back section 16 is turned upwardly from its horizontal position, the levers 49 again turn on the pivots 54 and the upper ends of said levers turn the rear legs 28 inwardly toward the back of the head section 16, as shown in Fig. 6, and at the same time the forward ends of the levers 49 act through the links 50 to restore the foot section 17 over the middle section 15. An important feature of the construction and relation of the levers 49, links 50 and lever bars 42, is that without disturbing the foot section 17 the head or back section 16 may be given the various adjustments or inclinations, shown in Fig. 4, when the article is in use as a couch, and may be given the adjustments indicated in Figs. 5 and 6 when the article is in use as a chair. I may increase the number of adjusted positions into which the head or back section may be placed, either when the article is used as a couch or as a chair, by providing an increased number of recesses in the rack plates 30 and lengthening the slots 52 in the links 50, as will be obvious.

The recesses in the rack-plates 30 are slanted downwardly, as shown in Figs. 5 and 6, so that there may be a very firm in-

terlocking of the pawl-rod 35 therewith in a direction to prevent downward movement of the head-section 16 except after said pawl-rod has been manually withdrawn from said recesses. During the upward movement of the head-section 16 the pawl-rod 35, being spring-pressed against the rack-plates 30, may ride out of the recesses of said plates, but when the said head-section is to be turned downwardly, the attendant will take hold of the middle portion of said rod 35 with one hand and pull said rod outwardly from the plates 30 and keep said rod spaced from said plates while with the other hand he is lowering said head-section.

In the modified construction shown in Figs. 8, 9 and 10, 60 designates the middle section, 61 the head or back section, and 62 the foot section of the general frame of the combined couch and chair. The foot section 62 corresponds exactly with the foot section 17 shown in Fig. 1, and the frames of the sections 60, 61 correspond with the middle and head or back sections of Fig. 1. The difference between the construction shown in Fig. 1 and that illustrated in Figs. 8, 9 and 10 resides in the lever mechanism whereby on the movement of the head or back section 61, the foot section 62 is slid outwardly from over the middle section 60 or returned over said middle section 60, as the case may be. In Figs. 8 and 9 the head or back section 61 is supplied with supporting legs 63, and to these legs are pivoted actuating levers 64 whose forward portions are pivoted at 65, and have pivoted to them the rear ends of links 66, whose forward ends are pivoted to lever bars 67 which are pivotally secured at their upper ends to the foot section 62 and at their lower portions are pivotally secured by rivets 68 to the side rails 69 of the middle section 60. The forward ends of the actuating levers 64 turn upwardly, as shown in Fig. 8, so that said levers 64 may, on the movement of the head or back section 61, impart either a rearward movement or a forward movement to the links 66 for turning the lever bars 67 on the rivets 68 and actuating the foot section 62. The levers 64 are provided with pawl pins 70 adapted to engage rack bars 71 formed on the pivoted yoke 72 which is secured at 73 to the rear legs of the middle section 60. The yoke 72 consists of a U-shaped bar, as shown in Fig. 10, and this bar is connected by springs 74 with a transverse bar 75 secured between the rear legs of the middle section 60. The springs 74 act to turn the forward portion of the yoke 72 upwardly and the rack bars 71 downwardly, in a position to engage the pawl pins 70. The lever bars 67 are connected by a spring 76 with the aforesaid transverse bar 75, and the purpose of the spring 76 is to assist the movement of the

lever bars 67 and foot section 62 toward the initial or chair position. In Fig. 8 the parts of the article are shown as extended to form a couch. When the article is to be converted into chair form the back section 61 is elevated, and this has the effect of turning the rear ends of the levers 64 upwardly and their forward ends downwardly against the rear ends of the links 66, with the result that the forward ends of said links will turn the lever bars 67 upwardly and toward the rear from their position shown in Fig. 8 to that illustrated in Fig. 9, said lever bars 67 during this movement first elevating the rear end of the foot section 62 and then sliding said section over the middle section 60 or to the position shown in Fig. 9. I provide the rack bars 71 with several teeth so as to permit the back section 61 to have several adjusted or inclined positions, the inclination of the back section 61 depending on which teeth of the rack bars 71 engage the pawl pins 70.

When the article is in chair position and it is desired to transform the same into a couch, the attendant will press with his foot on the forward side portion of the yoke 72 and thereby turn the rack bars 71 upwardly to free the pawl pins 70, and thereupon the attendant will press the back or head section 61 downwardly and thereby cause the forward portions of the levers 64 to turn upwardly and rearwardly and by drawing against the links 66 and lower ends of the lever bars 67, effect the forward movement of the upper portions of said bars 67 and the consequent pushing outwardly of the foot section 62 to its couch position.

The construction shown in Figs. 8, 9 and 10 carry out some of the purposes of my invention, but my invention is more satisfactorily represented when embodied in the construction shown in Figs. 1 to 7 inclusive, the rack bars then being secured out of the way to the upper portion of the back section 16 and the links 50 being slotted, as at 52, to permit certain adjustments of the said back section 16 both when the article is used as a couch and as a chair without disturbing the foot section 17. I secure adjustments of the head or back section 61 of Fig. 8 with the rack bars 71 arranged as shown in Figs. 8 and 9, but in the absence of the slots 52 of the links 50 shown in Fig. 1, the links 66 in Fig. 8 will not permit of adjustments of the back or head section 61, when the article is extended as a couch, without said links exerting their influence on the foot section 62. The links 66 of Fig. 8 may, however, be provided with the slots, such as 52 in Fig. 1, but due to the position of said links 66 with relation to the floor, it is not desirable to slot said links 66. It is believed the construction and operation of

the article shown in Figs. 8, 9 and 10 will be 65 fully understood in view of the detailed description of the construction shown in Figs. 1 to 7 inclusive.

In both of the constructions hereinbefore described the angle-iron side rails of the 70 foot or front section are slightly more widely spaced apart than the angle-iron side rails of the middle section so as to be slid over the same when said foot or front section is moved rearwardly, and in both of 75 said constructions the rear ends of the side rails of the foot or front section seat upon the forward ends of the side rails of the middle section and over the front legs of said section when said front section is in its 80 forwardly extended position, at which time the said foot or front section is firmly supported by its own front legs and by the front legs of the middle frame section.

What I claim as my invention and desire 85 to secure by Letters-Patent, is:

1. In a convertible chair and couch, a main frame comprising a middle or seat-section having rigid front and rear legs, a head-section pivoted to the rear part of said 90 middle section and having pivoted rear supporting legs and a front or foot-section having front supporting legs and being open at its rear end to slide over said middle section, actuating levers pivotally connected with 95 the legs of the head section and with the rear portion of said middle section, lever-bars pivoted at their upper ends to the rear portion of said front section and at their lower portions to the lower portion of said 100 middle section and links connecting said lever bars with the forward ends of said actuating levers, whereby on the movement of said head section said actuating levers may move said rear supporting legs and, through 105 said links, said lever bars to slide said front section outwardly to couch position or inwardly over said middle section to chair position.

2. In a convertible chair and couch, a 110 main frame comprising a middle or seat-section having rigid front and rear legs, a head-section pivoted to the rear part of said middle section and having pivoted rear supporting legs and a front or foot-section 115 having front supporting legs and being open at its rear end to slide over said middle section, actuating levers pivotally connected with the legs of the head section and with the rear portion of said middle section, lever-bars pivoted at their upper ends to the rear portion of said front section and at their lower portions to the lower portion 120 of said middle section and links connecting said lever bars with the forward ends of said actuating levers, whereby on the movement of said head section said actuating levers may move said rear supporting legs and, 125

through said links, said lever bars to slide said front section outwardly to couch position or inwardly over said middle section to chair position, said links having a loose connection with said lever bars so as to permit inclined adjustment of said head section when in couch position without affecting said front section, combined with pawl and rack mechanism for supporting said head section in 10 its inclined position.

3. In a convertible chair and couch, a main frame comprising a middle or seat-section having rigid front and rear legs, a head-section pivoted to the rear part of 15 said middle section and having pivoted rear supporting legs and a front or foot-section having front supporting legs and being open at its rear end to slide over said middle section, actuating levers pivotally connected with the legs of the head section and with the rear portion of said middle section, lever-bars pivoted at their upper ends to the rear portion of said front section and at their lower portions to the lower 25 portion of said middle section and links connecting said lever bars with the forward ends of said actuating levers, whereby on the movement of said head section said actuating levers may move said rear supporting legs and, through said links, said lever bars to slide said front section outwardly to couch position or inwardly over said middle section to chair position, said links having a loose connection with said lever 30 bars permitting said head section to be given inclined adjustments when in its couch and chair positions without affecting said front section, combined with pawl and rack mechanism for supporting said head section in its normal chair position and in its adjusted inclinations when in couch and chair positions.

4. In a convertible chair and couch, a main frame comprising a middle or seat-section having rigid front and rear legs, a head-section pivoted to the rear part of 45 said middle section and having pivoted rear supporting legs and a front or foot-section having front supporting legs and being open at its rear end to slide over said middle section, actuating levers pivotally connected with the legs of the head section and with the rear portion of said middle section, lever-bars pivoted at their upper ends to 50 the rear portion of said front section and at their lower portions to the lower portion

of said middle section and links connecting said lever bars with the forward ends of said actuating levers, whereby on the movement of said head section said actuating 60 levers may move said rear supporting legs and, through said links, said lever bars to slide said front section outwardly to couch position or inwardly over said middle section to chair position, said links being 65 slotted and connected with said lever bars by pins rigid therewith and extending through the slots of said links whereby a loose connection of said links with said lever bars is established permitting inclined 70 adjustments of said head section without disturbing said front section, combined with pawl and rack mechanism for supporting said head section in its positions of adjustment when its supporting legs are free 75 from the floor.

5. In a convertible chair and couch, a main frame comprising a middle or seat-section having rigid front and rear legs, a head-section pivoted to the rear part of 80 said middle section and having pivoted rear supporting legs and a front or foot-section having front supporting legs and being open at its rear end to slide over said middle section, actuating levers pivotally 85 connected with the legs of the head section and with the rear portion of said middle section, lever-bars pivoted at their upper ends to the rear portion of said front section and at their lower portions to the lower 90 portion of said middle section and links connecting said lever bars with the forward ends of said actuating levers, whereby on the movement of said head section said actuating levers may move said rear supporting legs and, through said links, said lever bars to slide said front section outwardly to couch position or inwardly over said 95 middle section to chair position, said levers, links and lever bars being arranged and 100 constructed to permit the head section to be given inclined positions of adjustment without disturbing said foot section, combined with pawl and rack mechanism for supporting said head section in its normal chair position and in its adjusted inclined 105 positions.

Signed at Brooklyn in the county of Kings and State of New York, this 28th day of June A. D. 1921.

JUDSON L. MCKELLAR.
